UNITED STATES PATENT OFFICE

CHARLES R. BUTLER, OF INDIANAPOLIS, INDIANA

ALLOY PISTON

Application filed March 13, 1929. Serial No. 346,517.

My invention relates to light-metal pistons for internal combustion engines, with an effective expansion control of such pistons.

It is the object of my invention to make a sturdy light-weight piston, as of aluminum alloy or other light-weight metal having a large co-efficient of thermal expansion, with substantially full circumferential skirt-bearing at least in the zone between the piston-pin bosses and the piston-ring belt and desirably also at or near the open end of the piston, and to produce an effective control of the expansion and contraction of the piston skirt, especially in that zone, so that it is more nearly equal to that of iron or steel; to reduce the internal stresses in the piston due to changes in temperature; to free from the piston-pin bosses the controlled skirt portions directly over such bosses, so that there may be relative movement between such portions and the bosses without the production of excessive bending stresses; to provide good heat conductivity between various parts of the piston so that the heat may be conducted away from the piston head even though not directly to the controlled zone of the piston skirt lying between the piston-pin bosses and the piston-ring belt; to provide for adequate transfer of heat from the piston to the cylinder; to reduce pounding and breakage, by so controlling the expansion and contraction of the piston that it fits closely within the cylinder at all temperatures through substantially the entire circumference in the zone between the piston-pin bosses and the piston-ring belt; to provide effective sealing against leakage of gas or oil, while yet permitting good lubrication; and to accomplish these results in a piston low in manufacturing cost and amply rugged to withstand the terrific loads to which pistons of heavy duty engines are subjected.

In carrying out my invention, I desirably make the piston as a whole of light metal, such as aluminum or aluminum alloy, and separate the head and piston-ring belt from the lower skirt portion or guiding portion by a circumferential slot so that stresses will not be transmitted from one to the other at or near the periphery of the piston; and pro-

vide carrying struts which connect the piston-pin bosses to the piston head, desirably at points on the latter fairly remote from the periphery thereof; and carry the skirt or guiding portion of the piston from the piston-pin bosses; and provide one or more endless steel bands, which are located in the piston skirt or guiding portion below such circumferential slot and at least one of which is located between said slot and the transverse plane of the piston-pin bosses; and slit longitudinally the light-metal portions of the skirt above the piston-pin bosses, and desirably at or near the longitudinal plane of such bosses, while permitting the endless steel band or bands to cross said longitudinal slits and complete the mechanical continuity of the skirt; and separate from the piston-pin bosses the skirt portions in the neighborhood of the aforesaid longitudinal slits so that those skirt portions may serve as guides without material distortion from the piston-pin bosses; and in some forms of my invention provide other longitudinally extending breaks in the light-metal portion of the piston skirt from the open end thereof up to or beyond the piston-pin bosses, or even to the said circumferential slot, but desirably at locations angularly spaced from the longitudinal plane of the piston pin.

The accompanying drawings illustrate my invention, and show six of the many forms it may take. One form is shown on Sheet 1, Figs. 1 to 5 inclusive; another form on Sheet 2, Figs. 6 to 10 inclusive; a third form on Sheet 3, Figs. 11 to 15 inclusive; a fourth form on Sheet 4, Figs. 16 to 21 inclusive; a fifth form on Sheet 5, Figs. 22 to 27 inclusive; a sixth form on Sheet 6, Figs. 28 to 31 inclusive; and a modification of the ferrous-metal control members also on sheet 6, Figs. 32 and 33.

In these drawings, Fig. 1 is a longitudinal section through one type of piston embodying my invention, the section being taken on the line 1-1 of Figs. 2, 3, and 4, in the longitudinal plane of the piston pin; Fig. 2 is a section on the line 2-2 of Fig. 1, and also substantially on the lines 2-2 of Figs. 3 and 5; Fig. 3 is a transverse section sub-

stantially on the lines 3—3 of Figs. 1 and 2; Fig. 4 is an elevation of the piston of Figs. 1 and 2, viewed in the same position as Fig. 2; and Fig. 5 is a transverse section substantially on the line 5—5 of Figs. 1 and 2: Figs. 6, 7, 8, 9, and 10 are views corresponding generally to Figs. 1, 2, 3, 4, and 5 respectively, but of a somewhat different specific embodiment of my invention, the sections on which Figs. 6, 7, 8, and 10 are taken being indicated by the lines 6—6, 7—7, 8—8, and 10—10 on others of those figures; Figs. 11 to 15 inclusive are also views generally corresponding to Figs. 1 to 5 inclusive respectively, but of a third specific form of my invention, the sections on which Figs. 11, 12, 13, and 15 are taken being indicated by the lines 11—11, 12—12, 13—13, and 15—15 on others of those figures; Figs. 16, 17, 19, and 20 are views generally corresponding to Figs. 1, 2 and 4, 3, and 5 respectively, but of a fourth specific embodiment of my invention, and Figs. 18 and 21 are an elevation and a bottom view respectively of the same piston, the various sections of which Figs. 16, the right half of 17, 19, and 20 are taken being indicated by the lines 16—16, 17—17, 19—19, and 20—20 on others of those figures; Figs. 23, 23, 24, and 26 are views corresponding generally to Figs. 1, 2 and 4, 3, and 5 respectively, but of a fifth specific embodiment of my invention, the sections on which Figs. 22, the right half of 23, 24, and 26 are taken being indicated by correspondingly numbered section lines on the other figures; Fig. 25 is a transverse section on the line 25—25 of Figure 23; and Fig. 27 is a perspective view of a steel strut which is shown by way of example in this fifth embodiment of my invention; Figs. 28, 29, 30, and 31 are views corresponding generally to Figs. 22, 23, 24, and 27, but showing a sixth embodiment of my invention, the sections of which Figs. 28, 29, and 30 are taken being indicated by correspondingly numbered section lines on others of those figures; and Figs. 32 and 33 are views corresponding generally to Figs. 29 and 30 respectively, but with a pair of overlapping arcuate strips each anchored at its end instead of the continuous control bands of the other figures.

In all these forms of my piston, there is a piston head 20 having a depending piston-ring-belt 21 provided with piston-ring grooves 22 for the usual piston rings; piston-pin bosses 23 which are located below the piston head and its ring-belt, and which co-operate with the usual piston pin, either directly or with suitable interposed bushings 24, such bushings being shown in the first form of my invention (Figs. 1 to 5) by way of example, although they may be used or omitted with any form of my invention; carrying struts 25 which extend from the piston-pin bosses at or near their inner ends to the head 20, desirably to join the latter in regions spaced inward

from the periphery of the head and from the ring belt, as in the first three and the preferred forms of my invention, so that such regions are intermediate regions between the center and the periphery of the head, although in some instances these struts or webs may also extend to and join the ring belt, as in the remaining forms which I have illustrated of my invention; and a guiding or skirt portion 26, which is suitably carried by the piston-pin bosses and serves as a cross-head to guide the movement of the piston in the cylinder. All the parts 20 to 26 so far described, with the possible exception of the bushings 24 when they are used, are usually made of a non-ferrous light metal, such as aluminum or aluminum alloy, which is light in weight and has certain desirable bearing-metal and heat-conducting characteristics. In addition, all the parts 20, 21, 23, 25, and 26 are desirably made as a single homogeneous casting, for ruggedness of construction and for high heat-conducting capacity.

The carrying struts 25 from the two piston-pin bosses to the head may be entirely separate from each other, as for instance in the forms of my invention shown in Figs. 6 to 15 inclusive; but for heavy work I prefer to interconnect them by a pair of webs 27 which extend from the head downward toward the piston-pin bosses in planes transverse to the struts 25, as shown in Figs. 1 to 5, so that the struts 25 and webs 27 together form a box-strut. This makes for great strength and ruggedness, and is especially desirable for pistons in heavy duty engines.

In all forms of my invention, the upper edge of the skirt or guiding portion 26 is separated from the lower end of the ring-belt 21 by a circumferential groove or slot 30; which may be either cut straight in, as for instance in Figs. 1 to 5 inclusive, or cut in conically, as in Figs. 6 to 15 inclusive, and which if desired may communicate with one of the piston-ring grooves 22 usually the lowest one, as in Figs. 1 to 5 inclusive, or may be slightly below and spaced from the piston-ring grooves, as in Figs. 6 to 15 inclusive.

The carrying struts 25 which connect the piston head to the piston-pin bosses may be substantially parallel to each other, and to the piston axis, as in the form of piston shown in Figs. 1 to 5 inclusive; or they may be inclined with respect to each other and to the piston axis, as in the forms of my invention shown in Figs. 6 to 10 and 11 to 15. These struts join the piston-pin bosses at or fairly near the inner ends of the latter, so that the struts are spaced inward from that portion of the piston skirt which lies between the circumferential slot 30 and the piston-pin bosses, to leave a space 31 between such struts and that portion of the piston skirt.

The piston skirt 26 may extend for substantially the full circumference of the piston

both above and below the transverse plane of the piston-pin bosses, as in the forms of my invention shown in Figs. 1 to 5 and 6 to 10; or it may be in the form of slippers, or side-thrust-carrying skirt-segments, in the transverse plane of the piston pin and between that plane and the open end of the piston, as in the other forms which I have illustrated of my invention. In all preferred forms of my invention, however, the piston skirt extends for substantially the complete circumference in a zone lying between the circumferential slot 30 and the transverse plane of the piston-pin bosses, save for certain slits which will shortly be described. That is, whether the skirt below the plane of the piston-pin bosses extends for the complete circumference or is merely a pair of slippers, above the plane of the piston-pin bosses it extends for substantially the full circumference, save for the slits referred to, so that there it will form a substantially complete guide for the piston throughout its circumference, not only in the plane of the thrust but also in the longitudinal plane of the piston pin so that rocking of the piston and wear on the piston rings will be minimized, and will also form a substantially complete embodiment for the control band or bands located in that zone and now to be described.

There are one or more such control bands embedded in the light-metal of the piston skirt. They are desirably endless steel rings, as indicated in all forms shown of my invention save that shown in Figs. 32 and 33. There is at least one such steel control band 35 in the zone just referred to, between the circumferential slot 30 and the transverse plane of the piston-pin bosses. This control band may be of any suitable cross-section, either rectangular or round, as shown in the various views of the drawings. It may be of any suitable iron or steel composition, to control the expansion of the piston skirt in its plane; so that it may be either ordinary iron or steel, or it may be of some ferrous-metal alloy (such as a nickel-steel alloy of which invar is one example) which has a co-efficient of thermal expansion less than that of cast iron or steel if in the design of the piston that lower co-efficient of thermal expansion is desired. Ordinarily I prefer that this control band have a greater co-efficient of thermal expansion than has invar, because the co-efficient of thermal expansion of invar is ordinarily too small for producing the best results; but invar may be used if desired. While I have shown only one ferrous-metal control band in the zone between the circumferential slot 30 and the piston-pin bosses, as that is sufficient to illustrate my invention, such invention is not at all limited to the use of only a single control band in that general location. But my invention does 65 contemplate the use of at least one control

band in that general location, whether or not more than one control band is used in that location, and whether or not a control band or bands are also used in other locations now to be described.

Thus in addition to a control band 35 in the zone just described, there may be one or more lower control bands 36, also of suitable ferrous metal, located in the zone between the transverse plane of the piston-pin bosses and the open end of the cylinder. These are especially desirable in the full-skirt type of piston, such as shown in Figs. 1 to 10 inclusive; although not essential to many forms of my invention, and thus not shown in the forms of my invention illustrated in Figs. 11 to 33 inclusive. That is, the lower control band 36 is not necessary to my present invention, although frequently desirable, but the upper control band 35 is essential to it.

The skirt 26 is carried from the piston-pin bosses 23. This carrying of the skirt from the piston-pin bosses is such that the skirt portions which lie between the transverse plane of the piston-pin bosses and the ring belt and in the neighborhood of the longitudinal plane of the bosses, are free from direct attachment to such bosses. To that end, the skirt may be attached to the piston-pin bosses in various ways. It may be directly continuous with the lower portions of the outer ends of the piston-pin bosses 23, as in the forms shown in Figs. 1 to 5 inclusive and 6 to 10 inclusive; with suitable strengthening webs interconnecting it to the bosses at 90 and below the plane of the piston-pin axis if desired; such as transverse webs 40 which extend from the piston-pin bosses out to the skirt as illustrated in Fig. 2, 3, and 4 and lie slightly below the transverse plane of the piston pin, or transverse webs 41 and oblique webs 42 which lie in and below such transverse plane as illustrated in Figs. 7, 8, and 10. These constructions are suitable for the full-skirt type of piston. If the skirt is of the slipper type below the transverse plane of the piston pin, it may be supported from the bosses by transverse carrying webs 43 which lie wholly or at least largely below the transverse plane of the piston-pin axis, as is illustrated in Figs. 11 to 15. The webs 43 are symmetrical with respect to the longitudinal plane of the piston pin. If desired, however, there may be such webs 43^a and 43^b which are unsymmetrical with respect to such plane, as is illustrated in Figs. 17 and 20, the webs 43^a extending from the open end of the piston up to and beyond the transverse plane of the piston pin, while the webs 43^b do not extend so high. The webs 43^a join the bosses to the thrust face which takes the side thrust on the explosion stroke of the engine, and are made to extend higher than do the webs 43^b so that they may be better able to do so. In the arrangement shown in 130

Figs. 22 to 33, the webs 44 which interconnect the skirt segments to the piston-pin bosses do not extend so high as the axis of such bosses, save where they join such bosses on 5 the underside thereof.

In any case, the portion of the skirt 26 in the zone between the circumferential slot 30 and the transverse plane of the piston pin extends for substantially the entire circumference, has embedded in it a control band 35, and in the regions which lie over or near the ends of such bosses is free from direct attachment to the bosses so that some relative movement between those regions and the bosses is 10 permitted.

The skirt portion which lies in this zone is provided with slits 45, which extend longitudinally of the piston and which are crossed by the control band 35 to complete the mechanical circumferential continuity of the skirt structure in spite of those slits. These slits 45 are thus only in the aluminum. Usually, and desirably, the slits 45 are located directly above the ends of the piston-pin 20 bosses, as shown in all the forms illustrated of my invention save that in Figs. 16 to 21 inclusive; but in that form they are shown as angularly shifted from that location toward each other on one side of the longitudinal 25 plane of the piston pin, usually but not always the side opposite that which is the thrust side of the explosion stroke. I prefer the symmetrical arrangement shown in the other figures, with the slits 45 substantially 30 in the longitudinal plane of the piston-pin axis; but the unsymmetrical arrangement shown in Figs. 16 to 21 inclusive, especially if combined with the unsymmetrical arrangement of the webs 43^a and 43^b, has certain advantages, especially when the side thrust is 35 heavy.

By reason of the slits 45, the skirt portion above the region around each end of the piston pin comprises one or two aluminum fingers 46. If the slits 45 are symmetrically arranged, as in all the forms of my invention shown except that in Figs. 16 to 21 inclusive, there are two such fingers 46, which project toward each other substantially free from 40 any immediate connection to the piston-pin bosses; and these fingers are joined, and the gap between them spanned, by the endless steel control band 35 which extends completely around the piston and in doing so projects from the end of each projecting finger 46 across the intervening gap formed by the slit 45 and into the finger 46 on the other side of such gap. If the slits 45 are arranged unsymmetrically, as in the arrangement 45 shown in Figs. 16 to 21, there may be only one such finger 46 over each piston-pin boss, which finger extends from the thrust face on one side (the left as shown in Fig. 17) over the piston-pin boss to the slit 45, here shown 50 arranged at the edge of the thrust face on the

other side (the right side as shown in Fig. 17).

The finger or fingers 46 may lie directly over the outer ends of the piston-pin bosses, as in the second, third, fourth, fifth, and sixth 70 forms of my invention, shown in Figs. 6 to 33 inclusive, in which case there may be a fairly wide slot 47 open to the outside of the piston skirt between the upper portion of the outer end of each piston-pin boss and the lower edges of the finger or fingers 46. This slot is crescent-shaped in the second and third forms of my invention, shown in Figs. 6 to 15 inclusive, in the third form of my invention extending downward to form the side edges of the lower parts of the thrust faces of the piston skirt. In the fourth form of my invention, shown in Figs. 16 to 21 inclusive, such slot 47 is like that in the third form on the side toward one thrust face, usually the 80 one which takes the thrust on the explosion stroke, though on the other side the upper edge of the slot extends horizontally along the under side of the finger 46 to the slit 45. In the fifth and sixth forms of my invention, shown in Figs. 22 to 33 inclusive, the fingers 46 are shown flat on their under sides, and spring only from the topmost parts of the thrust portions of the skirt; so that the slot 47 between the bosses 23 and such fingers 46 90 is apparently not in the shape of a crescent, although effectively it is still crescent-shaped. Thus in all of these forms of my invention, there is in effect a crescent-shaped separation 95 47 which separates the outer ends of the bosses 23 from the finger or fingers 46 which overlie such outer ends.

However, especially if the length of the piston is limited, the fingers 46 may lie radially outward beyond the outer ends of the upper parts of the piston-pin bosses, and at about the same height as such upper parts, instead of directly overlying the bosses. This is the situation in the form of my invention shown in Figs. 1 to 5 inclusive. In this case, the fingers 46, which lie radially beyond the outer ends of the upper portions of the piston-pin bosses, are separated from such upper portions of such outer ends by vertically extending slots 48, which lie just inside of the fingers 46. The slots 48 have the same general function as the generally crescent-shaped slots 47. It is usually in such cases as this that I may provide the bushings 24, although they are not necessary even here, so that if they are provided the slot 48 may not extend completely to the bearing surface of the piston pin. Any relative movement between the fingers 46 and the piston-pin bosses 23 in this construction will be by relative movement of the fingers toward and from the ends of the bosses, or along the bushings 24 if they are provided. To facilitate this, a slight clearance may be provided around the outer ends 100 of the bushings 24, although only a micro- 110

scopic clearance is usually provided and even that is not essential.

The lower end of the skirt, or the portion of the skirt toward the open end of the piston, is desirably provided with one or more longitudinally extending separating slots, which may be provided in various manners. Such separation may be the normally circumferential separation between the two slipper portions of which the skirt is constituted in the third illustrated form of my invention, shown in Figs. 11 to 15 inclusive; in which case the separation is a very wide one, of the order of 90° of circumferential extent, and the edges of the separating slots are the edges of the thrust faces or slipper portions of the skirt. On the other hand, such separation may be by one or more mere slits 50 extending upward from the lower end of the piston skirt, to about the level of the piston pin axis, or slightly above it, in Figs. 1 to 5 and other figures, or even to the circumferential slot 30, as shown in Figs. 6 to 10. Such slits may end in a drilled hole 52, shown in Figs. 1, 18, 22, and 28, to prevent the formation of cracks. The slits 50 may be wave slots, as shown in Fig. 1, or straight slots as shown in Figs. 6, 18, 22, and 28; and each straight slot may be along an element of the cylindrical surface, as in Fig. 6, or oblique to such cylindrical element as in Figs. 18, 22, and 28. The slits 50 are shown in all cases as angularly removed around the piston from the axis of the piston pin, although no particular angle is essential; and may be provided in one or both thrust faces, as illustrated in Figs. 16 to 33 and Figs. 1 to 10 respectively; and for simplicity are shown as open or non-sealing slots, although that is not essential. If the lower control bands 36 are provided, as in the first and second forms of my invention shown in Figs. 1 and 10 inclusive, they preferably cross the slits 50.

The upper control bands 35 may be the only steel control used. It may or may not be supplemented by the lower control band 36, as has already been pointed out. In addition, although it is not necessary, it may at times be desirable to supplement the control by the upper control band 35 with chordally extending ferrous-metal struts 55, on which the aluminum is cast to embed the end portions of the chordal struts in the skirt segments and the intermediate portions of the chordal struts in the bosses 23 and in the piers or carrying struts 25 which join the bosses 23 to the piston head. Such ferrous-metal struts may take various forms, of which I show only two very simple forms. In the form shown in Figs. 22 to 27 inclusive, such ferrous-metal struts are in the shape shown in Fig. 27, with obliquely bent ends 56 where they are embedded in the metal of the skirt segments, with a semi-circular notch 57 in their lower edges where they fit around the hole for the

piston pin, and with central upward extensions 58 where they are embedded in the carrying struts or piers 25. Here the ends of the struts 55 join and are embedded in the skirt segments in a plane below that in which the control band 35 is located, as is perhaps most clear from Fig. 23. In the form shown in Figs. 28 to 31, the ferrous-metal chordal struts 55^a are not upwardly offset at their middles and downwardly offset at their ends, as is the ferrous-metal strut 55 shown in Fig. 27, but lie in the same general transverse plane as does the upper control band 35, and are provided with obliquely bent ends 56 (the same as are the struts 55), which, however, have notches 59 in which the upper control band 35 lies. If desired, the control band 35 may be spot-welded to the struts 55^a where it passes through the notches 59. These forms of ferrous-metal struts 55 and 55^a are merely shown by way of example of many types of struts which may be used. When used, they help to control the expansion of the skirt between the circumferential slot 30 and the transverse plane of the piston pin, and also help to transmit side thrust from the piston-pin bosses to the skirt segments; but in the forms of my invention which I have so far found most successful, the chordal struts are not used in conjunction with the upper control band 35; so that I prefer the forms of my invention shown in Figs. 1 to 15 inclusive.

I prefer to use endless steel bands for the control bands. However, if desired, I may use overlapping arcuate strips 60 as shown for instance in Figs. 32 and 33. Each such arcuate strip extends across one of the slots 45, and as shown extends for something more than 180° of the circumference of the piston; so that by using two arcuate strips 60, the ends of one such strip overlap the ends of the companion arcuate strip, as is clear from the drawings. To get a balanced action, I prefer to set these strips slightly helically, so that each strip has one end over and one end under the adjacent end of the companion arcuate strip. This arcuate strip arrangement gives a somewhat greater control action than does the endless control band made of metal of the same co-efficient of thermal expansion; but I prefer the endless control band because of its freedom from joints.

In making the piston, the various ferrous-metal parts, such as the upper control band 35, and the lower control band 36 and the chordal struts 55 or 55^a when they are used, are suitably supported in the mold, and then the molten light metal, such as aluminum alloy, is poured into the mold to embed those portions of the ferrous-metal parts which the drawings show so embedded. The various slots and slits may be formed in molding, as by suitable slot-forming devices, or may be formed by sawing or other machine operations afterwards. I prefer to form the

wave slots 50 in the molding operation, and also the slits 45 and slots 47; but usually form the circumferential slot 30 by a machining operation subsequent to molding.

5 In operation, heat which is produced in the piston head by the explosions is transmitted by the carrying struts 25 to the piston-pin bosses, and thence to the piston skirt, whence it may be dissipated to the cylinder 10 and the cooling water.

In this operation, there are different rises in temperature in the different parts of the piston. The piston head naturally gets the hottest. This produces expansion, which is 15 substantially the same in all directions, and which is an expansion with the co-efficient of thermal expansion of the aluminum or aluminum alloy or other light metal used. The expansion of the head as it is heated causes the 20 carrying struts 25 to be separated somewhat, thus tending to carry the piston-pin bosses 23 slightly radially outward. The amount of such separation of the bosses 23 depends upon a number of factors, notably on the 25 deflection of such struts and the distance they are spaced apart where they join the piston head. The use of the webs 27 tends to prevent such deflection of the struts 25, by reason of the strength of the box-strut which 30 the carrying struts 25 and the webs 27 together form. The closer together the upper ends of the carrying struts 25 are placed, the less the forcing apart of the piston-pin bosses will be by reason of the expansion of the 35 head; because of the reduction in the intervening distance between them at the head where aluminum-expansion mainly occurs.

The separation of the bosses 23 is also opposed by the upper control band 35, and by 40 the lower control band 36 if it is present. However, the upper control band 35 permits some such expansion, for the piston-pin bosses may move outward slightly, while the fingers 46 do not move outward so far, if at 45 all, on account of the fact that the fingers 46 are free from direct attachment to the piston-pin bosses and are held by the steel control band 35 from moving out more than that control band permits. In consequence, 50 as the piston increases in temperature, both the space 31 and the slits 45 tend to narrow somewhat, as indeed do the slots 50 also when the lower control band 36 is used.

The narrowing of the slits 45 and of the 55 slots 50 is due to the differential expansion of the control bands 35 and 36 on the one hand and the aluminum alloy directly embedding them on the other hand, such control bands serving as tracks on which the aluminum slides circumferentially in such differential expansion. The narrowing of the 60 space 31 is due to the restraint against outward expansion exercised by the control band 35 on the fingers 46 as the piston-pin 65 bosses 23 are forced apart by the expansion

of the head. Such relative movement is permitted by the fact that the fingers 46 and the upper portions of the bosses 23 are separate from each other, so that any bending which may be incident to such narrowing of the 70 space 31 is so slight that it is not detrimental.

Because of these interactions of parts, the fingers 46 co-operate with the rest of the piston skirt to form an effective cross-head to guide the piston smoothly. The fingers 75 46 serve as firm supports for the piston in the neighborhood just above the regions at the end of the piston pin, for they are located between the ring-belt and the piston-pin axis where they are most effective in doing this. 80 These fingers 46 effectually prevent chattering of the piston against the cylinder wall in the line of the piston pin, and thereby reduce the wear on the piston rings and on the head section, and serve to hold the head section 85 properly in place.

I claim as my invention:

1. A composite piston, comprising a piston head and piston-ring belt, piston-pin bosses, carrying struts interconnecting said head 90 and said piston-pin bosses, a piston skirt carried from said piston-pin bosses, said skirt having portions which extend and lie between the bosses and the head, and which fill substantially the entire space between 95 said parts, and which portions are spaced from said carrying struts and are free from direct attachment to the upper sides of the piston-pin bosses and are provided with slits extending lengthwise of the piston, and a circumferentially extending control band of different metal from the aforesaid parts of the piston and embedded in the metal of the skirt between the ring belt and the transverse plane of the piston-pin axis and extending 100 across said slits, said ring belt and said skirt being separated by a circumferential slot.

2. A composite piston, comprising a head having a depending piston-ring belt, piston-pin bosses, carrying struts interconnecting said head and said piston-pin bosses and joining the latter near their inner ends, a skirt having thrust portions supported from said piston-pin bosses, said thrust portions having projecting fingers extending circumferentially of the piston in between and substantially filling the spaces between said piston-ring belt and the upper parts of the piston-pin bosses, each finger extending toward and almost but not quite to a cooperating finger 120 projecting from the other thrust portion so that a gap is left between each two fingers which project toward each other, said fingers lying in the transverse plane of the piston between the ring belt and the piston-pin axis 115 and being free from direct attachment to the upper parts of the piston-pin bosses, and a circumferentially extending control band of different metal from the skirt and fingers but 125 embedded therein and spanning said gaps be- 130

tween the adjacent ends of the fingers, said ring belt and said skirt and fingers being separated by a circumferential slot.

3. A composite piston, comprising a head having a depending piston-ring belt, piston-pin bosses, carrying struts interconnecting said head and said piston-pin bosses, a skirt having thrust portions supported from said piston-pin bosses, said thrust portions having projecting fingers extending circumferentially of the piston in between and substantially filling the spaces between said piston-ring belt and the upper parts of the piston-pin bosses, each finger extending toward and almost but not quite to a cooperating finger projecting from the other thrust portion so that a gap is left between each two fingers which project toward each other, said fingers lying in the transverse plane of the piston between the ring belt and the piston-pin axis and being free from direct attachment to the upper parts of the piston-pin bosses, and a circumferentially extending control band of different metal from the skirt and fingers but embedded therein and spanning said gaps between the adjacent ends of the fingers, said ring belt and said skirt and fingers being separated by a circumferential slot.

In witness whereof, I have hereunto set my hand at Indianapolis, Indiana, this 9th day of March, A. D. one thousand nine hundred and twenty-nine.

CHARLES R. BUTLER.
